UNITED STATES PATENT OFFICE

MAX M. HIRTENSTEIN, OF JAMAICA, NEW YORK

DESIGN FOR A GAME BOARD

Application filed February 20, 1931. Serial No. 38,741. Term of patent 7 years.

To all whom it may concern:

Be it known that I, MAX M. HIRTENSTEIN, a citizen of the United States, residing at 161-18 Normal Road, Jamaica, L. I., N. Y., in the county of Queens and State of New York, have invented a new, original, and ornamental Design for a Game Board, of which the following is a specification, reference being had to the accompanying drawings, forming part thereof, in which

Fig. 1 represents a plan view and Fig. 2 represents a side elevation of my game board.

I claim:

The ornamental design for a game board as shown.

MAX M. HIRTENSTEIN.
